UNITED STATES PATENT OFFICE.

FREDERICK ZIRKULY, OF BROOKLYN, NEW YORK.

REFRIGERATOR.

Application filed July 3, 1920. Serial No. 393,880.

To all whom it may concern:

Be it known that I, FREDERICK ZIRKULY, residing at the city of New York, borough of Brooklyn, Kings County, in the State of New York, have invented certain new and useful Improvements in Refrigerators, of which the following is a full, clear, and exact specification.

My invention relates to improvements in refrigerating apparatus, and the same has for its object more particularly to provide a simple, efficient and reliable apparatus by means of which the refrigerating medium may be protected against undue loss.

Further said invention has for its object to provide an apparatus in which the refrigerating medium is utilized to provide a source of cold air, which serves to surround or envelope the compartment containing said refrigerating medium as well as the compartments containing the articles of food or other substances to be preserved.

Further said invention has for its object to provide an apparatus having means for controlling the passage of cold air issuing from the refrigerating compartment and passing into and through the air space surrounding or enveloping said refrigerating compartment, and the other compartments communicating therewith.

Further said invention has for its object to provide an apparatus in which the several compartments may be severally automatically closed against each other or against the refrigerating compartment in order to prevent the loss of cold air therefrom when the doors of said compartments are opened.

Other objects will in part be obvious, and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings showing an illustrative embodiment of my said invention,

Figure 1 is a front elevation, partly broken away, showing one form of refrigerator constructed according to, and embodying said invention;

Fig. 2 is a vertical section on the line 2-2 of Figure 3;

Fig. 3 is a vertical section on the line 3-3 of Figure 1;

Fig. 4 is a horizontal section taken essentially on the line 4-4 of Figure 2; and

Fig. 5 is a detail sectional view showing the construction of the refrigerator casing.

In said drawings 10 designates a refrigerator comprising an outer casing 11 made of wood or other suitable material, and lined upon its inner side with a plurality of sheets of oil paper or the like, 12; a layer of wood 13, and an inner covering comprising a plurality of sheets of oil paper or the like, 14.

Within the outer casing 10 is disposed a smaller inner casing 15 of wood which is maintained in properly spaced relation to said outer casing by stays 16, so as to form an air space 17 between the top, bottom, sides and back of said inner and outer casings.

The inner casing 15 is provided upon its outer side with a plurality of layers of oil paper or the like 18, and upon its inner side with the usual metal lining 19.

The interior of the inner casing 15 is divided into three compartments 20, 21, and 22, by shelves 20^a, 21^a. The compartment 20 is adapted to receive a refrigerating medium such as ice, or other suitable refrigerating medium.

Within the refrigerating compartment 20 is provided an ice-tray 23 having a trough 23^a disposed below the same and connected with a drain pipe 24 having a trap 25 at its lower end without the box forming a water seal to prevent the entrance of warm air into the interior of the refrigerator.

The shelves 20^a, 21^a are each provided with a series of openings or slots 26, adapted to register with corresponding openings or slots 27 provided in plates 28, 29, arranged below said shelves 20^a, 21^a, respectively, and slidably supported in guides 30.

Upon one side wall of the inner casing 15, below the shelves 20^a, 21^a, are secured bearings or brackets 31, 32, respectively. Upon the upper bearings or brackets 31 is mounted a shaft 31^a to which is fixed a bell-crank lever 33 having the end of one of its members pivotally connected to the under side of the upper sliding plate 28, and the end of its other member pivotally secured to a link 34, whose lower end is pivotally secured to a disk 35 rotatably mounted upon the

lower bearing or bracket 32. 32^a denotes a shaft mounted in the lower bearings or brackets 32 upon which is fixed a bell-crank lever 36 having one end pivotally secured to 5 said link 34 and its other end pivotally connected to the under side of the lower sliding plate 29.

37, 38 denote latches of the two lower compartment doors 39, 40, respectively, which 10 latches are fixed to the shafts 37^a, 38^a, respectively. The disk 35 is fixed upon the shaft 38^a, and an arm 37^b is fixed to the shaft 37^a, so that when either of the latches is raised to permit of the opening of its 15 door, the bell-crank levers 33, 36 will be simultaneously actuated to cause the sliding plates 28, 29 to be moved and close the openings or slots in the shelves 20^a, 21^a.

To aid in shifting the sliding plates 28, 20 29, and maintaining the openings 26, 27 thereof out of register when the doors, or either of them, are opened, springs 41 are provided. One end of each spring is secured to the inner side of the inner casing 25 15, and the other end secured to each of the sliding plates 28, 29.

In order to permit the cold air from the refrigerating compartment 20 to pass into the air spaces 17, the side wall of the inner 30 casing 15, adjacent to the lower portions of the compartments 20, 21 and 22, is provided with separate series of openings or slots 42, and upon the outer side of said side wall of the inner casing 15 is provided a sliding 35 plate 43 provided with openings or slots 44 corresponding with the openings or slots 42 in said side wall. The sliding plate 43 has its upper end, which extends through the top of the outer casing 10, provided with a 40 handle portion or head 45. 46 denotes guides secured to the outer side of the inner casing 15 within which the sliding plate 43 works.

The outer casing 10 is provided at its top 45 with an opening or vent 47 which is normally sealed by a screw plug 47^a.

48 denotes a coil of pipe disposed within the refrigerating compartment 20 to provide a supply of cold water or other fluid. 50 49 denotes the inlet, and 50 the outlet for said coil.

The operation of the apparatus is as follows:

Ice is first placed into the refrigerating 55 compartment 20 and thereupon all the doors of the refrigerator closed. Thereupon the sliding plate 43 is lowered by means of the handle or head 45, and the openings 44 brought into register with the openings 42 60 in the wall of the inner casing 15, at each of the compartments 20, 21, 22. At the same time the vent 47 in the top of the outer casing 10 is opened by removing the plug 47^a.

The sliding plate 43 and the vent 47 are 65 permitted to remain open a sufficient length

of time to permit cold air to pass from the refrigerating compartment 20 into, and completely displace the warmer air occupying the space 17 between the outer casing 10 and the inner casing 15. When said 70 space is completely filled with cold air the slide 43 is moved upward and the openings 44 therein brought into register with the openings 42 in the side wall of the inner casing 15, and the plug 47^a again secured 75 in the vent 47. The inner casing 15 will thereupon be substantially enclosed by an envelope of cold air.

When either of the doors 39, 40 of the lower compartments 21, 22 is opened the 80 slides 28, 29 will be actuated to close the openings 26 in said shelves, and thus prevent the passage of cold air from any one of said compartments to the other thereof.

It will be noted that by means of my 85 improved construction the refrigerating medium, as well as the air cooled thereby, will be conserved to the greatest extent possible, and at the same time cold air will only be lost or impaired in the particular compartments to which the access is had for the 90 time being.

Having thus described my said invention, what I claim and desire to secure by Letters Patent is:—

1. An apparatus of the character described comprising an outer casing, doors therein, and an inner casing separated from said outer casing by an air chamber, a plurality of compartments in said inner casing, apertures in the partitions separating said compartments from each other, means for controlling the passage of air to and from said compartments, apertures in each compartment communicating with said air 105 chamber, means for controlling said last-named openings, and securing means for said doors for actuating the means for controlling the passages of air arranged between said compartments, substantially as 110 specified.

2. An apparatus of the character described comprising an outer casing, doors therein, locking means for said doors, and an inner casing separated from said outer casing by an air chamber, partitions in said inner casing serving to divide the same into a plurality of compartments, said partitions having openings therein, a sliding member associated with each of said partitions having openings therein adapted to register with the openings in said partitions, operating means serving to connect said sliding members together and with the locking means for said doors; said compartments 115 each having openings in one of their walls communicating with said air chamber, a sliding member associated with said wall and provided with openings adapted to register with the openings in said wall, 120 125 130

- means extending from the end of said last-named sliding member, through said outer casing, and means on the projecting portion of said last-named sliding member for actuating the same, substantially as specified. 5
3. An apparatus of the character described comprising an outer casing, doors therein, locking means for said doors, and an inner casing separated from said outer 10 casing by an air chamber, an opening in said outer casing communicating with said air chamber, means for sealing said opening, partitions in said inner casing serving to divide the same into a plurality of compartments; each compartment having its side 15 wall and its partition provided with series of openings, sliding members associated with each of said compartments for severally controlling the series of openings thereof, means for automatically actuating the sliding members associated with said partitions to control the passage of air from one of said compartments to the other upon the opening of the doors, and means for separately actuating the sliding member associated with the side wall of said compartments for controlling the passage of cold air from said compartments to said air chamber, substantially as specified. 20
- 25 4. An apparatus of the character described comprising a casing having partitions therein serving to divide the interior thereof into a plurality of compartments; said partitions having openings therein, means operatively associated with said partitions for controlling said openings, doors for said compartments, a locking device for 30
- 35 each door including a shaft, a link connected to said shafts, and pivoted members associated with each of said shafts and said link and connected to the means for controlling the openings in said partitions, substantially as specified. 40
5. An apparatus of the character described comprising a casing having partitions therein serving to divide the interior thereof into a plurality of compartments; said partitions having openings therein for establishing communication between said compartments, a sliding plate associated with each partition having openings therein adapted to register with the openings in its respective partition, doors in said casing for providing access separately to said compartments, a locking device for each door including a shaft extending through said casing, a lever fixed upon the outer end thereof, and a member fixed upon the inner end of said shaft and connected to the sliding plate of its respective compartment, and a link connecting the members fixed upon the inner ends of the shafts of said locking devices whereby to simultaneously actuate said sliding plates as either of said doors is operated, substantially as specified. 45 50 55
- 60 65

Signed at the city of New York, in the county and State of New York, this 9th day of December, one thousand nine hundred and nineteen.
